SPRAY GUN

Donald J. Peeps, Toledo, Ohio, assignor to The De Vilbiss Company, Toledo, Ohio, a corporation of Ohio

Application January 28, 1948, Serial No. 4,781

2 Claims. (Cl. 299—140.1)

1

This invention relates to a spray gun of the type utilizing compressed air for atomizing the spray material and particularly to such a spray gun in which the air stream passing therethrough is divided into two parts, one primarily for atomizing the material and the other for use in forming the spray discharge flattening jets.

A principal purpose of this invention is the provision of simple compact means for dividing the air.

Another object of the invention is the provision of an improved nozzle design.

A further object of the invention is to provide an easily adjustable retainer for the material valve packing and such a retainer that occupies a minimum space and also contributes to the good appearance of the spray gun.

Other objects and advantages of the invention will become apparent upon reading the following description with reference to the drawing in which:

Figure 1 is a vertical section of a spray gun embodying my invention;

Figure 2 is an elevation partly in section of the rearward mid-section of the spray gun shown in Figure 1;

Figure 3 is a horizontal section of the spray gun;

Figure 4 is a view of the forward end of the spray gun with the air cap, fluid tip and cap retaining sleeve removed;

Figure 5 is a rear elevation of the air divider ring; and

Figure 6 is a front elevation thereof.

The spray gun illustrated in the drawing has a main body 1 with air inlet connection 2 and spray material connection 3. From the connection 3 the material flows upwardly through vertical passage 4 into the horizontal bore 5 of the body insert 6. This insert is held within the body by a tight fit and set screw 7. From the insert bore 5 the spray material continues forwardly out the discharge port 8 in the spray material tip 9. The discharge port is normally closed by needle valve 10 the rear end of which extends axially of the bore 5 and to the rear end of the spray gun.

Near its rearward end the needle valve 10 has a cylindrical enlargement 11. The forward face of the enlargement receives the rearward needle opening thrust of fingers 12 which extend downwardly in straddling relation to the needle from the hub 13 of the trigger 14. The latter is pivotally mounted on the stud 15. Against the rearward face of the enlargement 11 is tensioned the

needle closing spring 16. This is housed within the adjustable screw 17 which also acts as a stop for the opening movement of the needle. In addition to the fingers 12 the trigger has a depending cam-like flange 18 which bears against a cylindrical plug 19. The latter is reciprocably located within a corresponding bore 20 in the gun body. The plug 19 has a deep transverse cut-away section 21 which provides space for the needle. Below the plug 19 and actuated by it is air valve 22. This valve controls the flow of air from connection 2 to passages 23 and 24 leading to the forward face of the spray gun body 1 surrounding the exterior portion of insert 6.

The air from these two passages 23 and 24 is maintained in separate paths by the divider ring 25. This ring has a flat annular forward face 26 which has a central bore 27. The bore is cylindrical in shape except at its bottom where it has a narrow inwardly extending flange 28. The edge of the flange is arc shaped terminating at its ends in flats lying in a common horizontal plane. The bore 27 fits over a cylindrical rib 29 on the insert 6. The rib is flattened at its top and bottom and the flats at the ends of the arcuate flange 28 of the ring 25 fit against the ends of the flattened bottom of the rib 29. The spray material tip 9 is threaded to the forward end of the insert 6 and has a rearward skirt 30 fitting over the rib 29.

A gasket 31 around the rib 29 between the skirt 30 and the ring 25 not only seals the adjoining surfaces of these elements, but also is the medium by which the skirt holds the ring against the forward face of the body.

On its rearward side the ring 25 has a generally cylindrical collar 32. This has an outwardly offset rounded bulge 33 on one side and a similar inwardly directed indentation 34 from the opposite side. The ends of the air passages 23 and 24 in the forward face of the body terminate respectively within the bulge and the indentation. The air from the passage 23 is thereby directed 45 within the collar 32 and the air from passage 24 is directed to the outside of the collar. The air within the collar travels forwardly through the spaces between the flattened top and the bottom of the rib 29 and the adjoining cylindrical surfaces of the divider ring 25, gasket 31 and the skirt 30 of the spray material tip 9. From the chamber 35 ahead of the rib this air continues forwardly through an annular series of ports 36 in the tip and is discharged around the outlet of 50 the tip through the central port 37 of the air

cap 38. The air on the outer side of the collar 32 flows forwardly through the slight opening between the outer rim of the divider ring 25 and the inner surface of the air cap retaining sleeve 39. This air then travels forwardly between the tip 9 and the air cap 38. The former is hexagonal in cross section with rounded corners, between the hexagonal flat surfaces, which fit the inner cylindrical surface of the cap. This air then flows through ports 40 in the cap and is directed exteriorly against the atomized spray material to flatten it into fan shape. As it is frequently desired to vary the width of the fan shaped discharge, a conventional air volume control valve 49 is positioned in intercepting relation with the rearward portion of air passage 24. The greater fan width desired, the more this valve is opened.

Within a socket 41 in the rear end of the body insert 6 is positioned a needle valve packing 42. This is held in place by threaded packing stem 43. This stem is thrust against the packing by nut 44 threaded to the stem within a rectangular port 45 extending transversely through the gun body. The longitudinal bore 46 in which the forward portion of the stem is located is cylindrical while the longitudinal bore 47 to the rear of port 45 is hexagonal in cross-section conforming to the hexagonal head 48 on the rear end of stem 43. This fit between the head and the hexagonal bore prevents the stem from rotating and when the nut 44 is turned rearwardly on the stem the nut bears against the rear wall of the port 45 and moves the stem forwardly against packing 42.

When it is desired to replace the packing, the needle valve 10, needle spring 16 and adjustable screw 17 are first removed from the rear end of the gun. The trigger 14 is released by removing stud 15 and plug 19 lifted out. The nut 44 is then turned forwardly upon the stem 43 and the latter is moved rearwardly until it is free of the nut and may itself be removed from the gun. The old packing may then be reached by a pointed tool and a new packing inserted. While this is more troublesome than replacing packing in some more conventional arrangements, replacement is needed only rarely, and this disadvantage is well compensated by the compactness of the subject design and the improved appearance it provides.

While I have shown and described a specific embodiment of my invention, it will be understood that various modifications may be made without departing from the spirit thereof as set forth in the appended claims.

Having thus described my invention, what I claim as new and desire to secure by Letters Patent is:

1. In a spray gun of the type described, a spray gun body with a flat annular surface at its forward end, the body having two air passages terminating in the flat annular surface with outlets spaced circumferentially apart but at points

radially equidistant from the longitudinal axis of the body, an air dividing ring having a rearwardly extending generally cylindrical collar fitting against the flat annular surface of the body, 5 an outwardly extending offset portion on one side of the collar overlying the outlet opening of one of said passages, an inwardly extending indentation on another side of the collar overlying the outlet opening of the other air passage, whereby 10 air from the first mentioned air passage is directed within the collar and air from the second mentioned air passage is directed to the outside of the collar, a spray nozzle mounted in front of the air dividing ring, with a central air discharge port and laterally positioned air discharge ports, and means directing air from the center of the ring to the central port and air from the outside of the ring to the laterally positioned ports.

2. In a spray gun of the type described, a spray gun body with a flat annular surface at its forward end and two separate air passages having their outlets on opposite sides of the annular surface at equal radial distances from the longitudinal axis of the spray gun body, an air dividing ring having a rearwardly extending generally cylindrical collar fitting against the flat annular face of the body, the inner diameter of the collar being substantially equal to the distance between the outlets of the two air passages, an outwardly extending offset portion on one side of the collar overlying the outlet of one of said passages, an inwardly extending indentation on the opposite side of the collar overlying the outlet opening of the other air passage, whereby air from the first mentioned passage is directed within the collar and air from the second mentioned passage is directed to the outside of the collar, and spray discharge nozzle means mounted on the forward end of the spray gun body in abutting relation to the forward end of the air dividing ring and having separate passages for the air from the interior and the air from the exterior of the ring and having separate discharge ports for the two streams of air.
